UNITED STATES PATENT OFFICE.

JOHN M. ADAMS, OF CHICAGO, ILLINOIS.

METAL BEDSTEAD.

1,130,873.

Specification of Letters Patent.

Patented Mar. 9, 1915.

Application filed May 22, 1911. Serial No. 628,695.

To all whom it may concern:

Be it known that I, JOHN M. ADAMS, a citizen of the United States, and a resident of Chicago, in the county of Cook and State 5 of Illinois, have invented certain new and useful Improvements in Metal Bedsteads, of which the following is a specification.

This invention relates to metal bedsteads.

As is well known, "ornaments" are commonly applied to the joints between different members of metal bedsteads for the purpose of imparting a neat finish and appearance to the bedstead, said "ornaments" being usually made of sheet brass or other thin 15 ductile metal.

The object of the present invention is to provide improved and simplified means for securing "ornaments" to other bedstead members without the use of screws, solder, 20 or other means heretofore commonly used for this purpose.

To this end my invention comprises the various features and details of construction hereinafter described and claimed.

25 In the accompanying drawing, in which my invention is fully illustrated, Figure 1 is a fragmentary side view of two hollow members forming part of the head or foot of a bedstead having an "ornament" secured thereto in accordance with my invention. Fig. 2 is a vertical sectional view thereof. Fig. 3 is a diagrammatic view substantially similar to Fig. 2, just before the connection is made and illustrating the manner of making the connection; and Fig. 4 is a sectional plan view on the line 4—4 of Fig. 2.

Referring now to the drawings, the reference numerals 1 and 2 designate, respectively, members of a metal bedstead, as, for 40 example, a tubular cross member of a head or foot of a bedstead, designated 1, and an upright rod or spindle, designated 2, connected thereto.

3 is an "ornament" applied to the joint 45 between said members 1 and 2 in accordance with my invention. The "ornament" 3 is secured in position by means of a section 4 at one end thereof, which is inserted through and which frictionally engages the 50 sides of a hole or opening 5 formed in the side of the hollow bedstead member 1. The end of the bedstead member 2 is inserted through the hollow "ornament" 3 into the first bedstead member 1, the relation being 55 preferably such that the member 2 will fit the hole through the section 4 of said "orna-

ment" closely and will thus operate to maintain said section 4 of the "ornament" 3 in frictional engagement with the side of the hole 5. As preferably constructed, the "ornament" 3 including the section 4 thereof is made on a slight taper, the size thereof decreasing toward its end designed to enter the hole 5. The small end of said "ornament" is preferably made slightly smaller 60 than the hole 5, and the designed position of said "ornament" is defined by contact of the surface of said tapered section with the sides of said hole or opening 5. The opening through the "ornament" 3, through 65 which the second bedstead member 2 passes, is also tapered slightly in substantially the same manner as the outer surface thereof, the relation being such that at its outer end said hole will fit the bedstead member 70 closely and the taper thereof being such that the initial diameter of said hole or opening 75 at the point where the outer surface thereof contacts with the side of the hole or opening 5, will be a slight fraction of an inch, say 80 1/100 of an inch, smaller than the size of said bedstead member 2 and the diameter of said section 4 beyond said point of contact with the sides of said hole 5 being still further contracted owing to the taper thereof. 85 Thus, as the member 2 is forced through the "ornament" 3 into the member 1, said member 2 will first operate to expand the section 4 of said "ornament" outwardly into strong frictional engagement with the sides of the 90 hole 5 and, as the end of said member 2 is forced beyond this point, will operate to expand the tapered end of said section 4, forming a crimp in the same at the point where it engages the sides of the hole 4, which will 95 operate in an obvious manner, to increase the strength of the engagement between the section 4 of said "ornament" and the sides of said hole 5. The initial taper of the section 4 of the "ornament" 3 is of advantage 100 for the further reason that it will prevent the "ornament" from being pushed into the hole 5 with the member 2, as said member is forced through said "ornament" into the hollow member 1. 105

I claim—

1. A bedstead comprising a first member which is hollow and is provided with a hole in the side thereof, a second member, and a hollow "ornament," said "ornament" comprising an expandable section inserted through the hole in said hollow first mem-

ber, and the second bedstead member inserted through said "ornament" into said hollow first member, the initial size of the section of said "ornament" which extends 5 through the hole in said hollow first member being substantially the same as said hole and the hole through said section of said "ornament" inserted through said hole being initially smaller than the bedstead member 10 which is inserted therethrough, whereby inserting said second bedstead member through said hollow ornament into said first bedstead member will expand the section of said ornament within said first bedstead member 15 into strong engagement with the sides of the hole in said first bedstead member, substantially as described.

2. A bedstead comprising a first member which is hollow and is provided with a hole 20 in the side thereof, a second member and a hollow "ornament," said "ornament" comprising an expansible section inserted through the hole in said hollow first member, and the second bedstead member in-

serted through said "ornament" into said 25 hollow first member, the section of said "ornament" which extends through said hole in said hollow first member being initially slightly tapered inside, and the hole through the tapered section of said "ornament" 30 being initially slightly smaller than the second member which is inserted through the same, whereby inserting said second bedstead member through said hollow ornament into said first bedstead member will expand the 35 section of said ornament within said first bedstead member into strong engagement with the sides of the hole in said first bedstead member, substantially as described.

In testimony, that I claim the foregoing 40 as my invention, I affix my signature in presence of two subscribing witnesses, this 18th day of May, A. D. 1911.

JOHN M. ADAMS.
